GUN

William E. House, United States Army,
Auburndale, Fla.

Application July 26, 1935, Serial No. 33,334

3 Claims. (Cl. 89—2)

(Granted under the act of March 3, 1883, as
amended April 30, 1928; 370 O. G. 757)

The invention described herein may be manufactured and used by or for the Government for governmental purposes, without the payment to me of any royalty thereon.

5 The subject of this invention is a gun and the invention is intended to so modify the Browning machine gun that the barrel may be held stationary to facilitate air cooling thereof.

10 The main object of the invention is to hold the barrel of a gun stationary while permitting the breech block and the barrel extension to perform their usual recoiling movements.

15 These objects are attained by separating the front portion of the barrel extension into which the barrel fastens from the remainder of the extension and securing it to the receiver and attaching a gas operated piston and rod to the barrel extension. The piston arranged to have the same amplitude of recoil as was originally 20 had by the barrel.

With the foregoing and other objects in view, as may more fully appear, the invention resides in the novel arrangement and combination of parts and in the details of construction herein- 25 after described and claimed, it being understood that changes in the precise embodiment of the invention herein disclosed may be made within the scope of what is claimed without departing from the spirit of the invention.

30 A practical embodiment of the invention is illustrated in the accompanying drawing, wherein:

Fig. 1 is a longitudinal sectional view of a gun constructed in accordance with the invention.

35 Fig. 2 is an enlarged detail sectional view through the lock.

Fig. 3 is an enlarged detail sectional view through the lock showing the gun in recoil.

Referring to the drawing by numerals of reference:

The gun consists of standard parts of the Browning machine gun having the receiver 1, barrel 2, bolt 3 and barrel extension 4 which has been modified by cutting off and enlarging the 45 forward end 5 into which the breech end of the barrel is threaded and making the portion fast in the receiver by rivets or in other suitable manner. The remainder of the barrel extension has added thereto a projection 6 which underlies the 50 member 5.

The projection 6 is slotted at 7 to receive a sliding lock 8 apertured to provide cam surfaces 9—9 adapted to cooperate with a cam 10 fast on a piston rod 11 which enters a bore 12 formed in 55 the projection 6 and communicating with the

slot 7. The rear counterbored end of the bore 12 receives a coiled spring 13 which surrounds the projecting end of the piston rod 11 and acts to retain the lock in elevated position.

5 The piston 14 carried on the forward end of the rod 11 works in a cylinder 15 secured to the forward end of the barrel 2 and adapted to receive gases from the barrel through a port 16 and to exhaust such gases through a port 17 so situated that the recoil of the piston and rod will cause a recoil in the barrel extension of the same amplitude as that formerly imparted to such part by the recoil of the barrel.

10 The lock 8 in its elevated position extends into a recess 18 to lock the barrel extension to the member 5.

15 The operation is as follows: When the gun is fired, gases escaping through port 16 enter the cylinder 15 and cause the piston 14 and rod 11 to move rearwardly. This movement causes the cam 10 to act on the lower cam face 9 of the lock 8 and cam the lock downwardly to unlock the parts. The barrel extension is then free to be moved rearwardly by the piston rod carrying and disconnecting the bolt for continued movement 20 in the usual manner.

25 As soon as the piston passes the exhaust port 17, the gas in the cylinder is free to escape and no further pressure is exerted on the piston so that the recoil of the barrel extension is the same 30 as that for which it was originally designed in the Browning gun.

35 During the operation of firing, the heavy aluminum jacket which is in intimate contact with the barrel dissipates the heat generated with sufficient rapidity to keep the barrel at a temperature below that which would prove injurious to the barrel.

I claim:

40 1. The combination with a gun including a receiver, a barrel extension in the receiver mounted for relative movement with respect to said barrel, a bolt in the receiver, of a member fast in the receiver, a barrel threaded in said member, a projection on the barrel extension below said member, a lock carried by the extension for locking the projection to the member, a cam for actuating the lock and imparting motion to the barrel extension, and a gas operated piston connected to the cam.

45 2. The combination with a gun including a receiver, a barrel extension in the receiver mounted for relative movement with respect to said barrel, a bolt actuated in recoil by the barrel extension, of a member fast in the receiver pro-

vided with a recess, a barrel threaded in said member, a projection on the barrel extension below said member, a lock carried by the extension and adapted to enter the recess for locking the projection to the member, a cam for actuating the lock and imparting motion to the barrel extension, a piston rod extending through the cam, a resilient element for forcing the cam to locking position, a piston on the rod, and means 10 for admitting gas pressure to said piston.

3. In a gun, a receiver, a barrel fixed in the

receiver, a member mounted for limited reciprocal movement in the receiver, an independently reciprocable recoil actuated bolt carried by said member and coupled to and uncoupled from said member during its forward and rearward movement, means carried by said member for locking it to the receiver, and a gas operated piston for unlocking the locking means and moving said member rearwardly.
